UNITED STATES PATENT OFFICE.

ALVA T. SMITH, OF WINSTED, CONNECTICUT.

HUMIDOR.

Application filed April 6, 1923. Serial No. 630,217.

To all whom it may concern:

Be it known that I, ALVA T. SMITH, a citizen of the United States of America, of Winsted, in the county of Litchfield, in the State of Connecticut, have invented new and useful Improvements in Humidors, of which the following, taken in connection with the accompanying drawings, is a full, clear, and exact description.

10 This invention relates to a humidifier adapted to be used more particularly in cigar and tobacco show cases, storage rooms and analogous containers although it is evident that it may be used in many other 15 relations such as cabinets, living rooms and the like where it is desired to supply a moist vapor.

The main object is to provide a simple and efficient device of this character comprising a container for the water or other suitable liquid to be vaporized and a hollow porous body or distributor combined in such a manner that the water or other liquid from the reservoir may be applied to one of the 25 surfaces of the porous body to be distributed by capillary force through the pores thereof, and liberated in the form of moist vapor to the atmosphere of the receptacle in which the humidifier is placed so that the 30 liberated moistened vapor may permeate the air in the receptacle or room for preservation of the articles therein or for hygienic purposes according to the use to which the humidifier is put.

35 Another object is to make the liquid container, or at least portions thereof, transparent so that the amount of liquid therein may be visible at all times and enable the user to replenish such liquid when exhausted.

40 A further object is to provide means for regulating the supply of liquid to one of the surfaces of the absorbent body and thereby to control the amount of moist vapor 45 liberated to the surrounding atmosphere.

Other objects and uses relating to specific parts of the device will be brought out in the following description.

In the drawings:

50 Figure 1 is an end elevation of one form of my invention in which the hollow absorbent body is external to the liquid container or reservoir.

Figure 2 is a longitudinal vertical sec-

tional view, partly in elevation, of the device shown in Figure 1.

Figure 3 is an end elevation, and

Figure 4 is a longitudinal vertical sectional view, partly in elevation, of a modified form of my invention in which the hollow porous tube is located within the liquid container.

Figure 5 is an end elevation, and

Figure 6 is a longitudinal vertical sectional view, partly in elevation of a further modified form of my invention somewhat similar to the construction shown in Figures 1 and 2 except that means is provided for controlling the flow of liquid from the reservoir to the porous body.

Figure 7 is a top plan of the central portion of the container shown in Figure 2 showing the means for indicating the position of the vent controlling valve in the liquid container.

The construction shown in Figures 1, 2 and 7 comprises a pair of upright end standards —1— connected by a tie-rod —2— and each provided with a pair of heads —3— and —4— having sockets —5— and —6—, the sockets —5— of the corresponding heads —3— being co-axial and facing each other for receiving the adjacent ends of a tubular reservoir or container —7— while the sockets —6— are disposed in a plane below that of the sockets —5— with their open ends facing each other and in co-axial alinement for receiving the adjacent ends of a hollow porous body —8—.

The supporting standards —1— extend below the porous body —8— and are provided with suitable feet —9— adapted to rest upon the floor or other suitable support of the receptacle or room in which the humidifier is placed, the upper ends of said standards being extended above the sockets —5— and are provided with apertures —10— to permit the entire device to be suspended from the top by suitable cables or other supports not shown.

The liquid reservoir —7— and porous body —8— are arranged in parallel spaced relation, one above the other, while the tie-rod —2— is located between and parallel with said container and porous body and has its opposite ends passed through registering apertures in the standards —1— and provided with nuts —11— engaging the outer

faces of said standards for tightly clamping the heads —3— and —4— against the opposite ends of the liquid container —7— and porous body —8—.

5 The container —7— is preferably made of transparent glass which is impervious to the liquid contained therein, and renders said liquid visible at all times to the user so that the container may be replenished with liquid, as water, when desired.

10 The opposite ends of the tubular container —7— are closed by plugs or stoppers —12— of cork or other suitable material inserted therein so as to form liquid-tight joints therewith, and are held against displacement by the ends walls of the heads —3—.

15 The upper side of the container is provided with an inlet —13— for filling purposes, said inlet being normally closed by a stopper —14— of cork or other equivalent material capable of forming a liquid-tight joint with the inlet.

20 An additional opening —15— is provided in the upper side of the container —7— and receives a bushing —16— of cork or equivalent material in which is inserted a cap —17— having a central tubular nipple —18— extending through the cork into the container to form a valve seat at its inner 25 end to cooperate with a valve —19—, said cap being also provided with an air vent —20— connecting the interior of the tubular nipple —18— with the atmosphere.

25 An adjusting screw —21— is mounted in a central aperture in the cap —17— at one side of the vent —20— and is connected by a spring —22— to the valve —19— whereby the valve may be adjusted relatively to its 30 set by turning the screw —21— in the proper direction to regulate the passage of air to the interior of the container through the vent —20— and thereby to regulate the quantity of water which may be fed from the container to the interior of the porous tube —8— in a manner presently described.

35 The hollow porous body —8— is preferably made in the form of a tube of any suitable material such as unglazed earthen-ware or any composite liquid-pervious material 40 capable of allowing the liquid admitted thereto to pass through the walls thereof by capillary attraction in a finely divided state sufficient to allow it to evaporate in the atmosphere at the surface thereof.

45 The opposite ends of the tubes are closed by suitable plugs or stoppers —23— of cork or equivalent material held in place by the adjacent heads —4— in such manner as to form liquid-tight joints therewith.

50 The major portion of the exterior of the tube —8— between the ends thereof is exposed to the surrounding atmosphere of the receptacle or room in which the humidifier is placed, but in some instances, portions of 55 the interior thereof, preferably near the

ends, may be coated at —24— with a water-impervious material to restrict the vaporizing area particularly if it is found that the porosity of the tube supplies an excessive amount of moisture at the surface.

70 The opposite corresponding ends of the container —7— and porous tube —8— are connected by U-shaped conduits —25— and —25'— having their lower ends inserted through registering openings in the caps —4— and adjacent plugs —23— into the adjacent ends of the porous tube —8— and their upper ends inserted through registering apertures in the caps —3— and adjacent plugs —12— into the corresponding ends of the tubular container —7— for permitting the flow of water, or other liquid, and air from the container —7— into the interior of the porous tube —8—.

75 The upper ends of the conduits —25— and —25'— are disposed at different levels below and above the axis of the container respectively, the one at the lower level determining the minimum level of liquid in the container while that of the upper level may supply the necessary air to the porous tube —24— to reduce the vacuum therein and permit the distribution of the liquid through the pores by capillary attraction to the exterior of the tube where it is liberated by vaporization to 80 the surrounding atmosphere.

85 It is, of course, evident that the flow of liquid from the container —7— to the porous distributing tube —8— may be regulated by the amount of air admitted to the container and this air may be regulated by the adjustment of the valve —19— through the medium of the screw —21— thus permitting the user to control at will, the amount of liberated moistened vapor from the distributing tube —8—.

90 As shown in Figure 7, the upper face of the cap —17— is provided with a circular 95 row of graduations around the adjusting screw —21— which is provided with a pointer —26— so that the position of the valve —19— relatively to its seat may be determined by the position of the pointer —26— relatively to the graduations on the cap —17—, all of which enables the user to determine the amount of liquid supplied to the interior of the porous tube —8— and, incidentally, the amount of evaporation liberated from the surface of said tube.

100 The construction shown in Figures 5 and 6 is somewhat similar to that shown in Figures 1 and 2 except that the central passage in the porous tube —8— is somewhat smaller in diameter and its walls are consequently thicker, and that the connecting tube as —25— at one end is omitted while the valve controlling the supply of liquid from the container —7— to the porous tube —8— is arranged in a connecting tube —25'— which takes the place of 105

the tube —25'— and is provided with a pair of radial nipples —27— projecting through registering openings in the head —3— and stopper —12— at different levels above and below the axis of the container —7— while the lower end of the conduit —25" — extends through registering openings in the head —4— and stopper —23—, whereby the liquid entering the conduit —25" — through the branch passages —27— of the container —7— enters the adjacent end of the porous tube —8—, the other end of which is closed by a stopper —23'— of cork or other suitable material.

15 The upper end of the pipe —25" — is provided with a cap —28— having an air vent —29— connecting the interior of the pipe with the atmosphere.

Communication between the lower end of the pipe —25" — and interior of the porous tube —8— is controlled by a valve —30— cooperating with a suitable outlet port —31— and provided with a stem —32— extending upwardly through a threaded opening in the cap —28—, the upper end being threaded and engaged in said opening for adjusting the valve —30— relatively to its seat to regulate the flow of water from the container —7— into the porous tube —8— and, incidentally, to regulate the flow of air through the communicating channels to break the vacuum in the container and porous tube and thereby to additionally regulate the amount of vapor liberated from the exterior of said porous tube to the surrounding atmosphere.

In the construction shown in Figures 3 and 4, the porous tube as —8'— is supported wholly within the tubular glass container —7'— with its axis below that of the container and its ends inserted in the stoppers —12'— in corresponding ends of said container to form liquid-tight joints therewith and with the porous tube.

45 The stoppers —12'— are held in place by end heads or caps —3'— which are placed over and upon the adjacent ends of the container —7'—.

One of the stoppers —12'— and adjacent end head —3'— are provided with registering openings —31— for filling purposes, said openings being normally closed by a stopper —32— of cork or equivalent material.

55 The passage through the porous tube —8'— is open at both ends and registered with corresponding openings —35— in the opposite caps —3'— to permit the passage of air therethrough.

60 That is, the porous tube —8'— is surrounded by the liquid in the container —7'— so that the liquid, as water, may permeate the walls of the tube by capillary force and vaporize in the interior thereof to enable the moisture-laden vapor to pass

out through the open ends of the porous tube to the surrounding atmosphere for supplying the required moisture to the objects in the receptacle in which the humidifier is placed.

70

The means for controlling the supply of moisture from the interior of the container —7'— to the interior of the porous tube —8'— is similar to that shown in Figures 1 and 2 and, therefore, the same reference numerals apply to corresponding parts of both devices.

75

If desired, the limited portions of opposite ends of the porous tube —8'— within the container —7'— may be provided with an exterior coating —24'— of water and air impermeable material to restrict the area to which the water is directly applied and thereby to reduce the quantity of vapor which may be liberated from the porous tube to the interior thereof as may be required according to the porosity of the tube.

80

If desired, the device shown in Figures 3 and 4 may be made of substantially the same size as any one of the cigars which may be placed in the box or case to take the place thereof, and when properly supplied with water, will preserve the cigars in the box or case from drying out or in the properly humidified condition against excessive drying out.

85

I claim:

1. In a humidifier, a closed water container and a hollow porous body having interior and exterior surfaces, and means for supplying water from said container to one of said surfaces to be conducted by capillary force through the pores of said body to vaporize at the other surface.

90

2. In a humidifier, a tubular water container having a water inlet and an air inlet, a stopper for the water inlet, a valve for the air inlet, means for adjusting the valve to regulate the amount of air admitted to the interior of the container, and a tube of porous material having inner and outer surfaces, one of said surfaces being exposed to contact with the atmosphere and the other surface exposed to contact with water from the container.

95

3. In a humidifier, a tubular water container, a porous tube parallel with the water container and provided with inner and outer surfaces, one of said surfaces being exposed to contact with the atmosphere, the other surface being exposed to contact with water from the container, and means for holding said container and porous tube in fixed relation to each other.

100

In witness whereof I have hereunto set my hand this 22nd day of March, 1923.

105

ALVA T. SMITH.
